UNITED STATES PATENT OFFICE.

SIEGMUND LOEWE, OF BERLIN-FRIEDENAU, GERMANY, ASSIGNOR TO RADIO CORPORATION OF AMERICA, A CORPORATION OF DELAWARE.

MEANS TO OPERATE ELECTROSTATIC TELEPHONES.

Application filed April 29, 1927, Serial No. 187,678; and in Germany February 20, 1924.

Telephones and loud speakers operating on basis of the electrostatic principles, for many reasons, are fundamentally more suited for the reproduction of signals and in wireless telephony work than the devices working according to the electromagnetic principles, for they involve neither hysteresis nor ohmic losses nor saturation phenomena, all of which are inevitable in electromagnetic processes. The demerit of electrostatic telephones and loud speakers resides in that the sensitivity of static means is very low, unless extremely high biasing potentials are resorted to. But the provision of such biasing potentials in practice is attended with great complications and danger, especially when supplied from batteries of accumulators or cells.

It is an object of the present invention to disclose ways and means to use electrostatic telephones and loud speakers both for the purposes of reproduction as well as for recording work, for instance, in lieu of microphones for modulating or controlling radio transmitters in which the drawbacks of the conventional devices are obviated.

In the first place, the requisite high constant biasing potential, according to the invention, is not obtained by means of batteries or cells; but rather by rectified radio frequency currents. It is possible in this manner to provide the required biasing potentials even in values of several thousand volts in a way free from danger and with a minimum amount of equipment.

From the method of producing high biasing potentials as here disclosed there may be derived further a number of novel circuit arrangements for reception work, and these shall also be described hereinafter, and they constitute part of the present invention.

In the accompanying drawing Figure 1 shows a circuit arrangement heretofore used including an electrostatic telephone wherein the high potentials required are obtained by the use of batteries or accumulators,

Figure 2 shows a circuit arrangement including an electrostatic telephone the high potentials for which are supplied according to my invention and

Figure 3 shows an improved receiving circuit utilizing an electrostatic telephone.

Figure 1 illustrates a receiving arrangement comprising an electrostatic receiver telephone of the kind heretofore customarily

used, in diagrammatic representation. Under practical conditions, a plurality of amplifier stages is used, it being understood that the requisite number of amplifier stages must be imagined as inserted in the circuits at the proper place.

Referring to Figure 1, 1 denotes the receiving antenna, 2 is a secondary circuit, 3 a grid condenser, 4 a leak resistance, 5 an audion tube comprising filament 6, grid 7, and plate 8. 9 is the heating battery, 10 the plate battery, 11 a high resistance, 12 the high-potential battery, 13 the static receiving telephone or the loud speaker.

The tube 5, as can be seen, is operated in an audion circuit arrangement. The potential fall across resistance 11 varying according to the incoming currents is added to the potential of battery 12 and results in corresponding acoustic actions in the loud speaker 13.

Now, according to this invention, the high potential 12 is produced in a way as shown in Figure 2. Instead of the battery 12, a condenser 14 is provided whose capacitance is high compared with the capacitance of the telephone. Connected with the said condenser 14 is a rectifier tube 15 in series with a coil 16 which, in turn, is coupled with a circuit 17 which is excited with high-frequency energy from a tube 18, for instance, in a voltage-divider scheme. The high-potential arising at the condenser 14 is entirely undangerous since, in case of accidental contact therewith, such an important potential drop is occasioned at once that no danger can exist any longer. Between condenser 13 and the potential source 14 a choke coil may further be inserted.

As regards the electrostatic telephone 13, the high potential thus produced acts in the very same way as a biasing potential derived from batteries.

As to the rest, the receiving actions are the same as shown in Figure 1.

However, it has to be noted that the method of deriving a variable potential across the terminals of a resistance 11, which is inserted in the plate circuit of an audion tube, is very unsatisfactory, since the said resistance 11, because of its necessary high value, renders the plate potential 10 largely ineffective in so far as the tube is concerned. On the other hand, any attempt of changing the variations of the plate current into high-

potential variations by the aid of transformers is impossible of practical realization seeing that the transformers required therefor would have to be provided with a 5 very high number of primary turns because of the low strength of the primary current flowing in the plate circuit, so that a still higher number of secondary spires would be needed to the end of insuring an increase 10 in potential. Transformers of this type are not only extremely expensive, but they also are of very low efficiency since the rise in potential is largely lost again by virtue of the internal capacity of the transformer.

15 However, the problem of transferring the modulated incoming currents to the electrostatic telephone in an efficient manner is easily solvable rather perfectly by that receiver circuit arrangements are used which 20 produce amplified, but also modulated receiving oscillations in the plate circuit of a tube, the frequency of these oscillations, as will be noted, not having to be the same as that of the incoming oscillations.

25 One embodiment of the scheme is shown by way of example in Figure 3.

The audion receiver arrangement is brought by way of a resistance 11 which is connected with the grid 19 of a tube 20 30 connected in a self-excitation scheme. The plate circuit 21 of this tube is as free from damping as possible and works with a small condenser and a large coil so that high potential amplitudes are obtained. Regeneration is produced by means of a coil 22 35 which is connected in series with a stopper condenser 23, a parallel resistance 24 being further provided, if desired. 25 is the plate battery of tube 20, 13 is the loud speaker, and 14 the condenser, to which, as shown in Figure 2, means for producing high potential is arranged in parallel. It will be noted, however, that coil 16 in this case may also be coupled directly with coil 21 so that 40 another tube 18 and a further oscillation circuit 17 may be dispensed with.

45 Now, the arrangement operates in the following way: Tube 20 would produce continuous waves of considerable amplitude, if 50 the latter were not considerably diminished by the condenser 23 or even entirely suppressed. This results in a negative charging of grid 19 whereby the plate current is choked. The (normal) current of tube 55 5 occasions a drop of potential across resistance 11 whereby also a negative potential is produced at the grid 19. However, as soon as currents come in, oscillations are produced in circuit 21, the potential 60 amplitude of which may be a multiple of

the amplitude which, according to Figures 1 and 2, would be set up across the resistance 11. This variable potential amplitude contacts with the constant biasing potential prevailing at condenser 14, and thus insures 65 efficient operation of the electrostatic telephone.

Also other control circuit arrangements in which local oscillations are released at the rhythm of the incoming signals, for 70 instance, arrangements in which tube 5 itself is connected in parallel relation to condenser 23 so that resistance 11 could then be dispensed with, operate in a similar way as the circuit arrangement last described.

75 I claim as my invention:

1. Radio signalling apparatus comprising a vacuum tube having plate and grid circuits regeneratively coupled together, means in series with the grid circuit for suppressing oscillations due to the regenerative coupling, an electrostatic telephone and a condenser in series, across a portion of the plate circuit of the tube, means for supplying a rectified high frequency current across 85 said condenser, and means for coupling the output of another tube in said radio signalling apparatus across the grid and filament of said first mentioned vacuum tube.

2. Radio signalling apparatus comprising 90 a vacuum tube having plate and grid circuits regeneratively coupled together, means comprising a condenser and a resistance in series with the grid circuit for suppressing oscillations due to the regenerative coupling, 95 an electrostatic telephone and a condenser in series, across a portion of the plate circuit of the tube, means for supplying a rectified high frequency current across said last mentioned condenser, and means for 100 coupling the output of another tube in said radio signalling apparatus across the grid and filament of said first mentioned vacuum tube.

3. Radio receiving apparatus comprising 105 an input circuit connected across the grid and filament of a first vacuum tube, means for coupling the output of said first vacuum tube to a second vacuum tube, a tuned circuit in series with the plate of said second tube and inductively coupled to an inductor in series with the grid of that tube, a circuit comprising a resistance and a capacity, in series with said inductor, an electrostatic telephone and a condenser in series, 110 across the tuned plate circuit, and means across said last mentioned condenser for supplying a rectified high frequency current thereto.

115 SIEGMUND LOEWE.
